BAIT TARGET

Martin D. Jaimet and Frank C. Kercher,
Indianapolis, Ind.

Application May 19, 1939, Serial No. 274,506

8 Claims. (Cl. 273—102.2)

This invention relates to a bait casting target. It has become quite common to hold bait casting contests or tournaments in which accuracy of casting is scored to determine the winners. Heretofore the scoring has been done by some individual by judging the location of the spot at which the plug drops. Such a method depends entirely upon the judgment of the individual and it is at once apparent that accuracy by such a method is almost impossible.

It is an important object of the invention to provide a target at which the plugs may be cast and which will indicate with accuracy not only a perfect cast or strike but also one or more values depending upon the nearness to the perfect cast. The target is suitable equally as well for both indoor and outdoor casting, either upon land or upon water. Ordinarily, in contests or tournaments, either $\frac{3}{8}$ or $\frac{5}{8}$ ounce plugs are employed.

When one of these plugs is cast, it often rebounds several times in a single cast so that controversy may arise as to the actual position of the original point of contact of the plug. At least after it has been cast and gone through a series of rebounds, there is no means for determining thereafter at what point the plug originally struck.

A further important object of the invention is to determine with certainty and indicate either visibly or audibly by a suitable signal the exact zone in which the plug originally struck and to prevent the showing of other signals upon subsequent rebound of the plug. In other words the invention provides a means for indicating with accuracy the exact zone in which the plug originally strikes and prevents the showing of other signals for rebound positions of the plug.

A still further important object of the invention is to provide a structure that will not only be suitable but will be reliable in operation over a long period of time and which can be adjusted for sensitivity to various weights of plugs employed.

These and many other objects and advantages of the invention will become apparent to those versed in the art in the following description as illustrated by the accompanying drawings, in which

Fig. 1 is a top plan view of a structure embodying the invention with part of the scoring floor broken away;

Fig. 2, a side elevation;

Fig. 3, a detail in vertical section on an enlarged scale on the line 3—3 in Fig. 1;

Fig. 4, a top plan view on an enlarged scale of an actuating switch;

Fig. 5, a side elevation of the switch; and

Fig. 6, a schematic wiring diagram.

Like characters of reference indicate like parts throughout the several views in the drawings.

A skeleton frame is formed by a plurality of arms 10, the number of which arms depends somewhat upon the desired diameter of the target. 10 In the form herein shown, six of the arms 10 are employed and are secured by their inner ends against respective faces of a hexagonal central block 11 and radiate therefrom to have, in the present showing, a circumferential enclosing band 12 secured to their outer ends. The top edges of these arms 10 terminate in a common plane.

A floor is provided to cover the arms and this floor consists of a central disc 13 with separate annular sections 14 and 15 arranged concentrically therearound and in slightly spaced apart relation. That is, there is an annular section 14 immediately surrounding the central disc 13 and then a second larger annular section 15 immediately surrounding the section 14 with a slight spacing therebetween. The top faces of the disc 13 and the two sections 14 and 15 lie in the same horizontal plane. The outer peripheral portion of the section 15 extends at least to the outer face of the side wall 12. The central disc 13 and the two sections 14 and 15 are carried by the arms 10 to permit vertical travel within certain limits.

For example, the outer section 15 is located and guided by having a plurality of posts 16, Fig. 3, secured to the section to extend downwardly therefrom through holes in brackets 17 carried by the arms 10. Two of these mountings are sufficient. The post 16, as indicated in Fig. 3, is in the present form secured against the under side of the floor section 15 by means of a screw 18 passing down through the section and screw-threadedly engaging the post 16 pulled up in abutment thereagainst. The lower end of the post 16 is provided with a stop on the under side of the bracket 17, the stop herein shown as being a cotter pin 19 passed through a hole in the post. To prevent binding of the post 16 in the hole through the bracket 17, the hole is preferably conically shaped so as to reduce contact of the bracket with the post to substantially a circumferential line. The cotter pin 19 is spaced downwardly along the post 16 a distance which will permit lifting of the section 15 a distance above the top edges of the arms 10.

55 In like manner the floor section 14 and also

the central disc 13 are tied to arms thereunder thus fixing the individual members of the floor to prevent shifting thereof laterally in any direction but permitting vertical travel within limits. Each of the three floor members 13, 14 and 15 are normally spaced in an upper position in a yielding manner whereby each section may be individually depressed without changing the elevation of the remaining members. In the present form, three of such supporting members are employed for each member although this number may be varied, of course, in accordance with the diameters of the respective members.

Referring to the disc 13, this disc is supported upon three equally spaced apart buttons 20. Each of these buttons 20 is carried upon a shiftable arm 21, Figs. 4 and 5, which is pivotally mounted at one end on a block 22. A block 22 is secured to every second arm 16 to secure the uniform spacing of the buttons 20, and the blocks 22 are further spaced along the respective arms 16 so as to bring them within a common circle within the disc 13. Referring again to Figs. 4 and 5, the arm 21 has a down turned foot 25 which passes between bracket arms 23 and 24 secured to the end of the block 22. Needle point bearings carried by the arms 23 and 24 engage the edges of the arm 21 so as to permit free swinging of that arm vertically. A screw 26 passes through the foot 25 toward the end of the block 22 to serve as a stop limiting the upward swing of the arm 21. A spring 27 engages an adjustable stud 28 which is mounted on a bracket 29 secured to the side of the block 22. The spring 27 extends from an end of the stud 28 to engage by its other end an arm 30 which is secured to the foot 25. By adjusting the length of the stud 28 relative to its bracket 29, the tension of the spring 27 may be varied accordingly and thereby determine the force required to push the arm 21 downwardly. Since the disc 13 rests directly upon the buttons 20 of the respective units thus described, the amount of pressure required to depress the disc 13 is controlled by the adjusting of the studs 28.

Under the free end of the arm 21 is provided a switch normally open and arranged to be closed upon depression of the button 20. In the form herein shown, this switch comprises two spring tongues 30 and 31, one insulated from the other and both mounted on the block 22. For sake of convenience, the floor unit supporting member and its switch is generally designated by the numeral 32. The floor section 14 is similarly supported by three additional units 32 carried by the arms 16 and arranged in a circle to bring them under the section 14. In like manner the floor section 15 is supported by three more units 32 arranged in a still greater circle to come under the floor section 15.

Any suitable type of signal may be employed such as an audible or visible signal, a visible signal being shown herein consisting of a lamp 33 responsive to depression of the disc 13, lamp 34 responsive to depression of the floor section 14, and lamp 35 responsive to depression of the floor section 15. These lamps may be mounted at any suitable location, either immediately at the signal or remotely therefrom. In the form shown, the lamps are mounted in a wall section 36 which may be pulled outwardly to permit access to relay and battery units carried therebehind.

The operation of the device may best be explained in reference to the wiring diagram, Fig. 6, wherein the units 32 in the top position repre-

sent those units operated by the central disc 13; the units 32 in the central position indicate those operated by the floor section 14; and the lowermost units 32 represent those operated by the outer floor section 15. For any one floor section the units 32 are connected in parallel one with the other in respect to their switch members 30 and 31. For the disc 13, these switch members 30 and 31 are connected in common with the wires 33 and 34 which lead to the terminals of a pair of tongues 35 and 36 respectively normally separated in a relay generally designated by the numeral 37.

From the terminal of the tongue 35, likewise 15 the terminal of the wire 33, is carried a wire 38 to a switch tongue 39 of a second relay generally designated by the numeral 40. This tongue 39 is normally in closed circuit with a tongue 41 and from the terminal of which tongue 41 leads 20 a conductor 42 to a switch tongue 43 in a third relay generally designated by the numeral 44. This switch tongue 43 is normally in a closed circuit with a tongue 45 of the relay 44. From the terminal of the tongue 45 leads a wire 46 to 25 a source of electrical current herein shown as a battery 47 which may be carried within the target unit immediately behind the wall section 36 adjacent the lamps 33, 34 and 35. From the other side of the battery 47 leads a wire 48 30 through a switch 49 to the relay 37 to connect with the winding 50 of the coil thereof. From the other terminal of the winding 50 leads a wire 51 to the terminal of the switch tongue 36 of the relay 37 and also the terminal of the wire 34.

35 Thus when any one or all of the switches of the units 32 under the disc 13 may be depressed upon impact of a plug dropped thereon, the circuit above traced is closed through the winding 50 of the relay 37. Since the winding 50 is about 40 a core 52, this core 52 will attract the relay armature 53 to lower it. The switch tongue 55 is engaged by an insulating block 54 secured to the armature 53 and is thus depressed upon dropping of the armature 53 to bring the switch tongue 35 45 into closed circuit contact with the switch tongue 36. However the circuit above traced still remains closed even though the switch members 30, 31 of any one or all of the units 32 be opened, such as by removing the bait plug from the floor disc 13.

50 The armature 53 of the relay 37 will remain down until that above described circuit is opened. When the armature is maintained in the lower position, it holds down a switch arm 55 in contact with a switch arm 56. The switch arm 55 is connected by a wire 57 with the wire 46 which leads to the battery 47, while the switch arm 56 is connected by a wire 58 with the lamp 33 in turn connected by a wire 59 with the battery 47 so as to include one or more cells at least of that battery between that connection and the connection with the wire 46 so that the lamp 33 is thereby energized indicating that the floor disc 13 has been struck by the bait plug.

55 Now should the bait rebound from the disc 13 to strike, for example, the floor section 14, the one or more units 32 under that section 14 will be depressed to close corresponding switch members 30 and 31, all of which are connected in parallel with the wires 60 and 61 leading respectively to the switch arms 62 and 63 in the relay 40, these arms 62 and 63 being normally spaced apart one from the other in open circuit. From the common terminal of the wire 60 and the switch arm 62 leads a wire 64 to a switch arm 65

in the third relay 44. This switch arm 65 is normally in contact with a switch arm 66. A wire 67 leads from the terminal of the switch arm 66 back to a switch arm 68 in the first relay 37 which then is spaced apart from the switch arm 65 since the winding 50 is still energized.

Since that spacing apart of the switch members 65 and 68 exists, no circuit is closed. In other words, energization of the relay 37 prevents downward movement of the floor section 14 from actuating any signal light and thereby only the lamp 33 indicates the initial striking zone of the bait as being within the area of the floor disc 13.

Now assuming again that the bait has initially struck the central floor disc 13 and rebounds to strike the outer floor section 15, the switch members 30 and 31 close in any one or all of the units 32 under the floor section 15 and thereby tend to close a circuit between the wires 69 and 70. Tracing a circuit from the wire 69, wire 71 leads therefrom back to the relay 37 to connect with the switch arm 72 in that relay which is then separated from the switch arm 73 to leave a gap in the circuit regardless of what else is connected thereto. Therefore, depressing the floor section 15 still does not close any circuit to its indicating lamp 35 by reason of the locking out action of the relay 37 initially actuated when the bait struck the disc 13.

Following the desired interval of display of the signal 33 for the initial score, the switch 49 may be opened manually or by any suitable time delay mechanism (not shown).

Then upon a second cast, it will be assumed that the plug strikes the floor section 14. In doing so that section 14 is pushed down to close any one or all of the switch members 30 and 31 to interconnect the wires 60 and 61. From the wire 60, leads the wire 64 to the switch member 65 of relay 44, this member 65 being normally in contact with the switch member 66 of the relay 44. From the switch member 66 leads the wire 67 to the switch arm 68 of relay 37. In this case, the switch arm 55 is in contact with the switch arm 68. From the switch arm 55 leads the wire 51 to the wire 46 which in turn leads to the battery 47. The circuit follows from the battery 47 through the wire 48 and its switch 49 through the wire 74, the winding 75 of the relay 40, and the wire 76 to the terminal of the wire 61 at the switch arm 63. This circuit energizes the winding of the relay 40 to shift its armature 77. In doing so the switch members 62 and 63 are closed one against the other to maintain the circuit just described following separation of the switch members 30 and 31 in the units 32. The movement of the armature 77 opens the circuit between the switch members 39 and 41 thereby opening circuit which normally includes the switch members 30 and 31 of the units 32 under the floor disc 13, thereby locking out any action resulting from shifting of the disc 13. Also the switch member 78 of the relay 40 is pushed against the switch member 79 to complete a circuit from the battery 47, wire 46, wire 51, wire 80, switch arm 78, switch arm 79, wire 81, signal lamp 34, wire 82, wire 59, battery 47. The lamp 34 is thus illuminated by reason of the floor section 14 having been depressed.

Now should the plug rebound from section 14 on to the central floor disc 13, the lamp 33 can not be illuminated by reason of the fact that the switch members 39 and 41 remain open in relay 40 preventing the closing of the circuit between the wires 33 and 34, through the relay 44 to the

battery 47 so that the relay 37 cannot be energized to close its switch arm 55 against the switch arm 56 to illuminate the lamp 33. Similarly, rebound of the bait from floor section 14 to floor section 15 will not cause the lamp 35 to become illuminated since the wire 71 leading from wire 69 (floor section 15) connecting with the relay 37, switch arm 72, switch arm 73, wire 83 and switch arm 84 in relay 40 finds an open circuit between that switch member 84 and the switch member 78 then shifted out of contact therewith. The signal lamp 34 remains illuminated until the switch 49 is opened whereupon the relay 40 returns to its normal position.

Assuming that the plug strikes the outer floor section 15, switch members 30 and 31 of any one or all of the units 32 thereunder interconnect the wires 69 and 70. From the terminal of the wire 69 at the switch arm 85 in relay 44 leads the wire 71 to relay 37 where it connects with the switch arm 72 then in contact with the switch arm 73. From switch arm 73 the wire 83 leads to the switch arm 84 in relay 40. Switch arm 78 is then in contact with the arm 84 and the wire 80 leads from the switch arm 78 to the wire 51, wire 46, and battery 47. From the battery 47 the circuit continues through the wire 48, its switch 49, the wire 86, winding 87 of the relay 44, wire 88 to the terminal of the wire 70 at the switch arm 89 of the relay 44. Thus a circuit is completed between the wires 69 and 70 through the battery 47 energizing the coil 87 to shift the armature 90 of the relay 44 to the "hold" position maintaining the circuit just described. In doing so, the arm 45 is pushed against the arm 91 of the relay to close the circuit from the wire 46 through the wire 92, lamp 35, wire 59, and battery 47. Should the bait rebound to either the floor section 14 or the central floor disc 13, neither lamp 34 or 44 is illuminated by reason of the open circuits maintained through the relays as above indicated.

It is, therefore, to be seen that only that section upon which the plug initially drops operates to give a signal thereby indicating the exact zone of the initial striking of the plug regardless of how the plug may bounce or rebound and subsequently strike other parts of the target.

While we have herein shown and described the invention in the one particular form, it is entirely obvious that structural changes may be employed such, for example, as the addition of float means for carrying the target upon water, using a greater number of zones than the three indicated, employing audible signals instead of visual signals, and varying the actual mechanical skeleton framework as well as the particular mounting and location of the switching and relay units. We, therefore, do not desire to be limited to that precise form beyond the limitations as may be imposed by the following claims.

We claim:

1. In a bait casting target, a plurality of horizontally placed floor zone members one adjacent another; normally open, electric circuit closing members under each zone member; means under each zone member yieldingly supporting the member and allowing the member to be depressed to actuate said circuit closing members upon pressure being applied to that zone member; an electrically operated signal for each zone member; a source of electrical current; a relay having an energizing winding; a circuit including said electric closing members for one of said floor zone members, said source of current, and said winding; a second circuit closed by said relay to

include one of said signals and said current source; a second relay having an energizing winding; and circuits maintained in open condition upon actuation of the first relay through contacts in said first relay, including said second relay winding, said other signals, and said current source, withholding said other signals from operation upon depression of their respective floor zone members.

2. In a bait casting target, a plurality of horizontally placed independently movable face sections; a circuit closer for each section actuated by travel thereof; elastic means resisting said section travel; an electrically operated signal for each of said sections; a source of current; circuits between each of said closers, the respective section signals, and said current source; and electro-responsive means interposed in said circuits causing a section signal to operate and acting to hold open circuits to all of the other of said signals irrespective of subsequent travel of the sections corresponding to those other signals, after travel of the section initially moved.

3. A bait casting horizontally placed target comprising a central disc, planar rings concentrically surrounding said disc, a plurality of like supporting members under said disc and said rings, each of said members comprising an arm extending thereunder, a downturned leg, a mounting member rockably carrying the arm, and a spring interconnecting said leg with said mounting member to urge the arm to lift said disc or rings, screw means for adjusting the tension of the spring, a foundation structure comprising spaced apart arms carrying said mounting members, means locating and retaining said disc and rings in separated relation on said foundation and permitting limited travel therefrom as induced by said springs through said arms, comprising a bracket with a hole, and a post with a stop sliding through the hole, electric circuit closing members normally open and closed by travel of said arms in opposition to said springs, and a signal for each of said circuit closing members, a relay means actuated by travel of one of said arms rendering inoperative closing members of other arms upon subsequent travel of those other arms.

4. A bait casting horizontally placed target comprising a central disc, planar rings concentrically surrounding said disc, a plurality of like supporting members under said disc and said rings, each of said members comprising an arm extending thereunder, a downturned leg, a mounting member rockably carrying the arm, and a spring interconnecting said leg with said mounting member to urge the arm to lift said disc or rings, screw means for adjusting the tension of the spring, a foundation structure comprising spaced apart arms carrying said mounting members, means locating and retaining said disc and rings in separated relation on said foundation and permitting limited travel therefrom as induced by said springs through said arms, comprising a bracket with a hole, and a post with a stop sliding through the hole, electric circuit closing members normally open and closed by travel of said arms in opposition to said springs, and a signal for each of said circuit closing members, and electro-magnetic means in circuit with a source of current, said signals energized upon closure of said closing members, switching means operated by said magnetic means for holding open circuits to all other signals following operation of any one signal, and

switch means for interrupting the circuit including said electro-magnetic means.

5. In a bait target, a plurality of horizontally placed target sections independently shiftable; a circuit closer for each section; a bank of switches for each section; a winding of an electro-magnet for each bank for actuating said switches; an electrically operated signal for each of said sections; a circuit from said closers including the winding of its respective bank switch magnet and a normally closed switch in each of the other switch banks, and said current source, whereby the energization of the winding for one bank shifts the switches therein to open its normally closed switch in said circuit and thereby prevent energization of the windings in any other bank; a normally open switch in each of said banks for each of said winding circuits closing upon energization of the winding of its bank to hold closed the winding circuit following operation and opening of its respective closer; and a circuit through a normally open switch in each bank including its respective signal and said current source closing only upon energization of the winding of its bank.

6. In a bait target, a plurality of horizontally placed target sections independently shiftable, a circuit closer for each section; a bank of switches for each section; a winding of an electro-magnet for each bank for actuating said switches; an electrically operated signal for each of said sections; a circuit from said closers including the winding of its respective bank switch magnet and a normally closed switch in each of the other switch banks, and said current source, whereby the energization of the winding for one bank shifts the switches therein to open its normally closed switch in said circuit and thereby prevent energization of the windings in any other bank; a normally open switch in each of said banks for each of said winding circuits closing upon energization of the winding of its bank to hold closed the winding circuit following operation and opening of its respective closer; and a circuit through a normally open switch in each bank including its respective signal and said current source closing only upon energization of the winding of its bank, and switch means for selectively interrupting each of said winding circuits.

7. In a bait casting target, a base; a central floor member; and a plurality of encircling floor members; all of said floor members being initially in substantially the same plane but separated one from the other; guides interconnecting the members with said base to permit travel normal thereto; stops limiting outward travel of the members; a plurality of L-shaped members carried by said base to have one leg of each extending along under said floor members in spaced relation one from another and to have the other leg of each downturned; a spring interconnecting each downturned leg with said base normally lifting the upper leg to urge the floor members yieldingly outwardly from the base; a normally open electric switch in the path of each of said L-members; a multiple contact relay for each floor section; an electrically operated signal for each floor section; a source of electric current; and circuits between said source, relays, signals, and switches arranged to have the closing of a section switch energize its respective relay and its respective signal, and simultaneously interrupt circuits between all other section switches, and their relays and signals.

8. In a bait casting target, a base, a central

floor member, a plurality of other floor members separated one from the other; guides interconnecting the members with said base to permit travel normal thereto; stops limiting outward travel of the members; a plurality of members carried by said base having a portion of each extending along under said floor members in spaced relation one from the other with a portion thereof downturned; a spring interconnecting each downturned portion with said base to urge the floor members yieldingly outwardly from the base; a normally open electric switch in the

5 path of each of said downturned portions; a multiple contact relay for each floor section; an electrically operated signal for each floor section; a source of electric current; and circuits between said source, relays, signals, and switches arranged to have the closing of a section switch energize its respective relay and its respective signal, and simultaneously interrupt circuits between all other section switches and their relays and signals.
